VALVE MECHANISM

Percy B. Levitt, Millburn, and Thomas Anderson,
Roselle, N. J., assignors to Cities Service Re-
search and Development Company, New York,
N. Y., a corporation of New Jersey

Application September 9, 1950, Serial No. 183,962

6 Claims. (Cl. 121—164)

1

This invention relates to valve mechanisms, and is more especially concerned with valves designed to admit and discharge air to the cylinder of a compressed-air-driven pump.

It is an object of this invention to provide a simple and sturdy valve mechanism for use in a high speed compressed-air-driven pump, particularly for use in handling grease or other viscous materials, such as the high pressure greasing apparatus disclosed in U. S. Patent No. 2,007,113.

It is a further object of this invention to provide a valve mechanism in which all operating and actuating parts are completely enclosed and protected against dust and dirt, and in which the valve plungers are self-lubricating.

It is still another object to provide a valve structure in which the air inlet and outlet ports can be made of relatively large cross-sectional area compared to the overall size of the valve structure, and which, when in open position, are not obstructed by valve stems or other objects tending to offer resistance to the free flow of air through the ports.

In order that those skilled in the art may more fully appreciate the construction of the new valve mechanism and its manner of operation, it will be more fully described in connection with the accompanying drawings, in which

Fig. 1 is a view, partly in cross-section, of a grease dispensing apparatus of the type disclosed in U. S. Patent 2,007,113, and incorporating the improved valve mechanism of the invention.

Fig. 2 is a plan view of the principal operating parts of the valve mechanism as viewed from above,

Fig. 3 is a cross-sectional view of the principal operating parts of the valve mechanism taken on line 2—2 of Fig. 2.

Fig. 4 is a vertical cross-sectional view of the valve and air cylinder as it would appear when in a position to admit air to the cylinder, and

Fig. 5 is a vertical cross-sectional view of the valve and air cylinder as it would appear when in a position to exhaust air from the cylinder.

Referring more particularly to Fig. 1, grease is placed in a pressure reservoir 1 fitted with an air-tight cover plate 2, to which air may be admitted through an air line 3. When air under pressure is admitted to the reservoir 1, the grease will tend to be forced out of the pressure reservoir 1 through a line 4 fitted with a foot valve 5 into the pumping cylinder 6 of an air-operated pump 7. When operating with soft grease, it may not

2

be necessary to place air pressure in reservoir 1, but when operating with hard greases, pressures from 100 to 300 p. s. i. may be necessary to force the grease into pumping cylinder 6. On the downward stroke of the piston plunger 10, foot valve 5 will close and grease will be forced through a grease line 11, provided with a check valve 12, to an appropriate grease gun (not shown), and on the upward stroke of the piston plunger 10, foot valve 5 will open, and grease will be delivered from the pressure reservoir 1 through the line 4 into the pumping cylinder 6.

Referring now more particularly to Figs. 4 and 5, in Fig. 4 it will be noted that valve plunger 37' is in raised position so as to permit free flow of air into the air cylinder 19 of the pump through intake air port 44 whereas valve plunger 38' is in lowered position, so as to close off exhaust port 45 and prevent the escape of air therethrough. Compressed air, entering the cylinder 19 through port 44 and its associated air passage 42, will then force the piston 16 and plunger 10 downward, forcing grease into grease line 11. As the piston 16 nears the end of its downward stroke, as illustrated in Fig. 5, it will make contact with an actuating rod 13, shifting the rod downward. This downward shifting of the rod 13 will, as will more particularly be explained hereafter, cause the valve mechanism 50 to snap into the position shown in Fig. 5, in which position valve plunger 37' will block off air port 44, shutting off the flow of air to the cylinder, while valve plunger 38' is in retracted position, opening exhaust port 45 to allow air to escape from the cylinder.

With exhaust port 45 open, pressure in the cylinder will rapidly be reduced to atmospheric, and the piston 16 will be returned to the position shown in Fig. 4 by spring 47, compressed between the piston 16 and the bottom wall 18 of the cylinder 19. As the piston approaches the upper end of its stroke, it will again make contact with actuating rod 13, this time shifting the rod upwardly. This upward shifting of the rod 13 will cause the valve mechanism 50 to snap back into the position shown in Fig. 4, and the piston will begin its downward stroke under the influence of air admitted through port 44.

As shown in Figs. 4 and 5 actuating rod 13 fits loosely with a hole, slightly shorter than the length of the piston stroke, in the piston plunger 10, the rod 13 having an enlarged head 14 at the lower end thereof, of such size and shape as to make contact with a bushing 15 at the upper end 55 of the hole in the piston plunger 10 when the

piston is at its lowest position, as illustrated in Fig. 5. The upper portion of the actuating rod 13 passes through a stuffing box 20 in the upper wall 21 of the air cylinder 19 and the base plate 22 of the valve assembly, the base plate 22 being secured to the upper wall 21 as by bolts 22'. It will be appreciated, of course, that the various parts of the valve mechanism may be mounted directly on or in the upper wall 21, in which case the base plate 22 may be dispensed with, but for ease in servicing and replacing the valve mechanism, the unitary valve structure illustrated in the drawings is preferred. The end of the actuating rod 13 fits within a hole 23 in a block 24 and is attached thereto as by a set screw 25, although any other means of attachment may be used. The hole 23 preferably extends through the block 24 in order to facilitate adjustment of the rod 13. The block 24, which is provided with slots 26, is slidably mounted on a vertical post 27 which is attached to the base plate 22 of the valve assembly in any convenient manner, such as by threading it into base plate 22.

The block 24 is connected by a pair of resilient members such as springs 30, to the middle joint 31 of a toggle member 32, the upper arms of which are connected to a fixed pivot, illustrated in the drawings as a rod 33 passing through the post 27 and the slots 26 of the block 24. The lower arms of the toggle member 32 are hingedly connected to a pair of rocker arms 34 near one end thereof, the rocker arms 34 being pivotally mounted on a pair of spaced lugs 35 affixed to the base plate 22 of the valve assembly. In order to achieve economy of space, the rod 13 and post 27 are centrally located between the rocker arms 34. The rocker arms 34, which may be braced as by studs 36 connecting their ends, carry a pair of blocks 37 and 38 into which are fitted valve plungers 37' and 38', the blocks being held in position by pins 39 and 40 passing through slots 41 in the rocker arms 34. Obviously, the cross-sectional area of the valve plungers 37' and 38' may be widely varied without affecting the size of the other parts of the valve mechanism, and may be of such area that the air cylinder 19 may be rapidly filled and evacuated without appreciable back-pressure due to friction in the intake and exhaust lines, thus enabling the pump to be continuously operated at high speeds.

Preferably, when the plungers are equidistant from the rocker arm pivot, as illustrated, they are of equal cross-sectional area, in order to balance the forces acting against each end of the rocker arm. However, if they are spaced at unequal distances from the pivot, their respective cross-sectional areas should be such that forces resulting from air pressure in the cylinder are balanced, so that the valve will not shift from one position to another in the middle of the upward and downward strokes of the piston.

Valve plunger 37' moves slidably within and operates to control the intake air port 42 and valve plunger 38' similarly operates to control the exhaust air port 43. Intake air port 42 connects with air line 3 by an air passage 44, which is threaded to receive a standard air connection, and exhaust air port 43 is connected with an air passage 45, which vents to the atmosphere.

Those parts of the valve assembly lying above the base plate 22 are protected against dust and dirt by a cover plate 46, attached to the base plate 22 as by bolts 47. It will also be observed that the actuating rod 13 is entirely enclosed within the pump, and is protected from any out-

side interference while the pump is in operation.

Referring now more particularly to Fig. 4, which illustrates the position in which the valve parts would be when starting up the pump, air 5 is admitted to the cylinder 19 through intake air passage 44 and intake air port 42. Air will now flow into the cylinder 19, forcing the piston 16 down to a position at which the shoulder of the enlarged head 14 on the end of the actuating rod 13 will come into contact with the bushing 15 at the upper end of the hole in the piston plunger 10. A further downward movement of the piston plunger 10 will pull the actuating rod 13 with its attached block 24 downward causing the center 15 line of the springs 30 to pass, in a downward direction, the fixed pivot 33 of the toggle member 32. As they pass this fixed pivot, the springs 30 will cause a downward resultant force to be applied to the middle joint 31 of the toggle member 20 32 causing the rocker arms 34 to snap rapidly to the position shown in Fig. 5, in which position the air intake port 42 will be closed by its associated valve plunger 37' and at the same time the exhaust air port 43 will be opened, by withdrawal 25 of its associated valve plunger 38'.

The piston 16 will then start on its upward journey under the influence of the spring 17. Near the end of the piston stroke the end of the rod 13 will come in contact with the bottom of the hole in the piston plunger 10, tending to force the rod 13 upward. As the actuating rod 13 moves under the influence of the pump piston 16, it will move the block 24 upwards, and cause the center line of the springs 30 to cross the fixed pivot 33 of the toggle member 32. The resultant force exerted by the springs 30 on the middle joint 31 of the toggle member 32 will then be in an upward direction moving the rocker arms 34 rapidly back to the position shown in Fig. 4, moving intake valve plunger 37' upwards and allowing air to flow into the air cylinder 19 through the inlet air port 42, and at the same time causing the exhaust valve plunger 38' to move downward to block off the exhaust air port 43. Air may now flow into cylinder 19 to start the piston on its pumping stroke.

When operated in an upright position, the valve stems and the operating rod may be made self-lubricating by placing a layer of oil on the 50 surface of the base plate. It has been found that, with the valve plungers 37' and 38' and air ports 42 and 43 machined to fit so that no air will be blown upward past the valve plungers, and when using leather packing in the stuffing 55 box 20 through which rod 13 passes, there is no leakage of oil into the air cylinder after long periods of use, and the rod and valve stems need no additional lubrication.

Having now described our invention, what we 60 claim as new and useful is:

1. A valve assembly, including in combination a base plate, a rocker arm pivotally mounted on said base plate, valve plungers connected to each end of said rocker arm, and operable to control 65 the flow of air through an inlet air passage and an outlet air passage in said base plate, a vertical post mounted on said base plate, a toggle member connecting one end of the rocker arm with a fixed pivot on the post, a block slidably mounted on the post, a resilient member connecting the center pivot of the toggle mechanism and the block, and means for moving the block along the post whereby to cause the center line of the resilient member to pass from one 70 side of the fixed pivot to the other.

2. A valve assembly including in combination an air cylinder, a rocker arm pivotally mounted on one end of the cylinder, valve plungers connected to each end of said rocker arm and operable to control the flow of air through an air inlet passage and an air outlet passage in the said cylinder, a vertical post mounted on the cylinder, a toggle member connecting one end of the rocker arm with a fixed pivot on the post, a block slidably mounted on the post, a resilient member connecting the center pivot of the toggle member and the block, a rod connected to the block and passing into the interior of the air cylinder, and means for moving the said rod and attached block whereby to cause the center line of the resilient member to pass from one side of the fixed pivot on the post to the other.

3. A valve assembly including in combination an air cylinder, a rocker arm pivotally mounted on said cylinder, valve plungers connected to either end of said rocker arm and operable to control the flow of air through an air inlet passage and an air outlet passage in the said cylinder, a vertical post mounted on the cylinder, a toggle member connecting one end of the rocker arm with a fixed pivot on the post, a resilient member connecting the center pivot of the toggle member with a rod passing into the interior of the air cylinder, and means for moving the said rod whereby to cause the center line of the resilient member to pass from one side of the fixed pivot on the post to the other.

4. A valve assembly including in combination an air cylinder, a piston reciprocably movable in said air cylinder, a rocker arm pivotally mounted on said cylinder, valve plungers connected to either end of said rocker arm and operable to control the flow of air through an air inlet passage and an air outlet passage in said cylinder, a vertical post mounted on said cylinder, a toggle member connecting one end of the rocker arm with a fixed pivot on the post, a block slidably mounted on the post, a resilient member connecting the center pivot of the toggle member with the block, a rod connected to the block

and passing into the interior of the air cylinder, the said rod being connected to the piston by means of a lost-motion connection in such manner that the rod will be moved by the piston at each end of its stroke for a distance sufficient to cause the center line of the resilient member to pass from one side of the fixed pivot on the post to the other.

5. A valve assembly including in combination an air cylinder, a piston reciprocably movable in said air cylinder, a rocker arm pivotally mounted on said cylinder, valve plungers connected to either end of said rocker arm and operable to control the flow of air through an air inlet passage and an air outlet passage in said cylinder, a vertical post mounted on said cylinder, a toggle member connecting one end of the rocker arm with a fixed pivot on the post, a resilient member connecting the center pivot of the toggle member with a rod passing into the interior of the air cylinder, the said rod being connected to the piston by means of a lost-motion connection in such manner that the rod will be moved by the piston at each end of its stroke for a distance sufficient to cause the center line of the resilient member to pass from one side of the fixed pivot on the post to the other.

6. The valve assembly according to claim 5 in which the valve plungers are of such cross-sectional area that the resultant forces directed against each end of the rocker arm due to air pressure in the cylinder are substantially equal.
